UNITED STATES PATENT OFFICE.

JOSEPH SOSS, OF BROOKLYN, NEW YORK.

METHOD OF MAKING HINGES.

Original application filed December 15, 1924, Serial No. 753,863. Divided and this application filed March 9, 1925. Serial No. 14,037.

This invention relates to hinges and particularly to what are known as covered joint hinges wherein the separate butts of the hinge are fashioned from sheet metal; and the object of the invention is to provide a hinge of the class specified, one of the butts of which is formed from a strip of sheet metal, one end portion of said strip being fashioned to form a hook-shaped end portion and a knuckle within the hook-shaped end portion whereby said knuckle forms the pivot portion of said butt and the hook-shaped portion thereof forming a hood for partially closing the pivot portion of the butt; a further object being to provide a hinge of the class described, one of the butts of which is fashioned from sheet metal and the end portion thereof being curved and fashioned to form a hood having top and bottom walls, and a pintle bearing within said hook-shaped end portion; a still further object of the invention being to materially simplify the construction of a hinge of the class under consideration whereby the manufacturing costs are reduced and a strong and durable hinge produced; and with these and other objects in view, the invention consists in a hinge of the class specified and in the improved method of producing the same hereafter more specifically set out in the specification and claims.

The invention described and claimed herein is a division of application bearing Serial No. 755,863, filed Dec. 15, 1924, now Patent No. 1,614,324, dated January 11, 1927, and is fully disclosed in the following specification, of which the accompanying drawing forms a part, in which the separate parts of my improvement are designated by suitable reference characters in each of the views, and in

which:—

Fig. 1 is a face view of a hinge made according to my invention with part of the construction broken away;

Fig. 2 is a plan view of a blank or a part of a blank from which one butt of the hinge is formed and indicating the first step in fashioning said blank.

Fig. 3 is a side edge view of the blank shown in Fig. 2 and illustrating the next step in the operation.

Fig. 4 is a view similar to Fig. 3 but showing another step;

Fig. 5 is a plan view of one end portion of a hinge butt diagrammatically illustrat-

ing the next step in the process of making the same.

Fig. 6 is a side edge view of the construction shown in Fig. 5 but showing the result of an additional trimming operation.

Fig. 7 is a longitudinal sectional view through the separate butts of the hinge with part of the construction broken away; and,

Fig. 8 is a plan view of the pivot ends of the separate butts of a hinge showing a slight modification in the formation of one of the hinge butts.

My invention relates to the construction of what are known as covered joint hinges and particularly to the construction of hinges of this class of two sheet metal hinge butts, and more particularly to the construction of the hinge butt provided with the means for covering or partially covering the joint of the hinge.

In carrying my invention into effect, I provide a blank in the form of a strip or sheet of metal 10 of predetermined dimensions and in constructing the hinge from said blank, the corner portions at one end thereof are cut out as indicated in dot and dash lines at 11 in Fig. 2 of the drawing, leaving at said end portion a projecting tongue member 12 of less transverse dimensions than the remainder of said blank. The end portion of the blank including the tongue member 12 is then fashioned to form a curved end portion 13 and in this operation the tongue member 12 is brought into engagement with one face of the blank 10 and the shoulders 14 formed by the cut out corner portions 11 are arranged at 15 an angle to the blank 10 as clearly seen in Fig. 3 of the drawing.

The next step in the formation of the hinge butt consists in arranging the curved end portion 13 into position to facilitate the fashioning of said end portion into predetermined formation, which result may be readily accomplished by the angular positioning of the shank of the blank thus formed as indicated in full and dotted lines in Fig. 4 of the drawing. By means of suitable dies, the curved end portion 13 as well as the tongue member 12 is swaged or compacted to form thereof a curved hood portion 15 within which is a pintle bearing 16, the hinge being recessed at the opposite sides of the pintle bearing as shown at 17 to receive the knuckles or pintle bearings on the other part of butt of

the hinge; the above result being produced by dies which depress the shoulder portions 14 and curved end portion 13 of the blank when positioned substantially as shown in Fig. 4 to force the metal into position to form comparatively thin walls 18 at the opposite sides of the bearing 16 which constitute part of the hood, said walls 18 gradually increasing in dimensions or thickness in extending 10 into the plate of the hinge butt as clearly illustrated at 19 in Fig. 6 of the drawing. It will be understood that in the above forming operation a shoulder 20 is formed at the edge of the hood portion 15 and upon the periphery 15 of the bearing 16.

In the above operation of forming the hinge, a flare of the metal as diagrammatically illustrated at 21 will result and the flares will be trimmed off in the next or 20 trimming operation on the hinge.

The next step in forming the hinge consists in shaping and sizing the same which will include the rebending of the hinge from the full line position shown in Fig. 4 back 25 into the dotted line position, after which the small aperture 22 formed within the bearing 16 in its making, is bored or reamed to suit the size of a predetermined pintle pin 23. It will also be understood that in the above described operation of fashioning the side portion of the blank to form the recesses 17 at the opposite sides of the bearing 16 and in the general shaping of the said end portion of the blank, a rough pin may be inserted into 35 the aperture 22 to prevent the collapsing of the tongue 12 which partially forms the bearing 16.

It will be understood that with the construction shown in Figs. 1 to 7 inclusive, that 40 the knuckles or bearing 24 of the hinge butt 25 are exposed through the top and bottom faces of the hinge (note Fig. 1 of the drawing) the hood 15 extending around the knuckles 24 to partially close the same and to form a covered joint hinge. However, in Fig. 8 of the drawing I have shown a modification in which the top and bottom faces of the knuckles 28 are closed by walls 26 formed integral with the blank 10 or integral 45 with the curved end portion of said blank and one of these walls is shown in said figure, and these walls are apertured as shown at 27 to receive the pintle pin 23, and the apertures 27 may open outwardly through the 50 walls 26 as indicated at 28 which facilitates the cutting of the apertures 27 which are angular particularly in one of the walls 26 to receive the angular shank or portion of a pintle pin to prevent the rotation of said pin in the 55 hinge butt formed from the blank 10. It will be understood however, that I am not necessarily limited to the specific formation of the aperture 27 herein set out, nor am I limited to the specific shape or form of the curved end 60 or hood portion of the hinge butt, and the 65

pintle bearing within said hood portion, and various changes in and modifications of the construction herein shown and described and the method herein shown and described and the method herein set out may be made, within the scope of the appended claims, without departing from the spirit of my invention or sacrificing its advantages.

It will be apparent that in the finish trimming, sizing and shaping of the hinge butt fashioned from the blank 10, the top and bottom faces of the pintle bearing 15 may be finished and brought to predetermined spaced relation to receive the other butt of the hinge, and the recesses 17 cleaned out if necessary 70 to provide the free action of the separate butt members one upon another.

Having fully described my invention, what I claim as new and desire to secure by Letters Patent, is:—

1. The herein described method of making a hinge butt which consists in providing a suitable blank, removing a portion of the metal at one end portion of said blank to form a projecting portion of less dimensions 90 than the remainder of the blank, bending said projecting portion and the adjacent part of the blank into substantially cylindrical formation, then compacting the metal of the folded end portion of the blank thus formed to form of said reduced portion and adjacent part of the blank a pintle bearing having recesses at the opposite sides of said bearing impressed on the blank surface, and then trimming and finish sizing the blank 95 to form the hinge butt.

2. The herein described method of fashioning a hinge butt from sheet metal to provide at one end portion of the butt a hood substantially covering the joint of the hinge and a pintle bearing within said hood, which consists in providing a sheet metal blank, curling one end portion of the blank to form the curved hood portion and a substantially cylindrical member within and partially formed by said curved hood portion, compacting the metal of said hood portion and member to form a sized pintle bearing and recesses at the opposite sides of said bearing and within said hood member, portions of the metal of the blank thus formed being flared, and then trimming the flared metal and finish sizing the workpiece to form the hinge butt.

3. The herein described method of forming a sheet metal hinge butt provided with an integral hood and pintle bearing which consists in providing a sheet of metal of predetermined thickness, removing predetermined portions of one end of the blank to form on said end a projecting part, curling said part and the adjacent portion of the blank to form of said part a substantially cylindrical member and of the adjacent part of the blank a curved hood portion, then com-

pacting said member and said hood portion at the opposite sides of said member to form a substantially cylindrical pintle bearing of said member and arc-shaped recesses disposed at the opposite sides thereof, the thickness of the walls of which are of less dimensions than the thickness of the metal sheet employed.

4. The herein described method of forming
10 a sheet metal hinge butt provided with an integral hood and pintle bearing which consists in providing a sheet of metal of predetermined thickness, removing predetermined portions of one end of the blank to form on
15 said end a projecting part, curling said part and the adjacent portion of the blank to form of said part a substantially cylindrical mem-

ber and of the adjacent part of the blank a curved hood portion, then compacting said member and said hood portion at the opposite sides of said member to form a substantially cylindrical pintle bearing of said member and arc-shaped recesses disposed at the opposite sides thereof, the thickness of the walls of which are of less dimensions than the thickness of the metal sheet employed, and forming in said compacting operation a stop shoulder on the hood and pintle bearing.

In testimony that I claim the foregoing as
30 my invention I have signed my name this 2nd day of March, 1925.

JOSEPH SOSS.
